UNITED STATES PATENT OFFICE.

THOMAS J. COLBURN, OF ARGENTA, ARKANSAS.

SWITCH-THROWING DEVICE.

No. 822,230.

Specification of Letters Patent.

Patented May 29, 1906.

Application filed October 27, 1905. Serial No. 284,713.

To all whom it may concern:

Be it known that I, THOMAS J. COLBURN, a citizen of the United States, residing at Argenta, in the county of Pulaski, State of Arkansas, have invented certain new and useful Improvements in Switch-Throwing Devices; and I do hereby declare the following to be a full, clear, and exact description of the invention, such as will enable others skilled in the art to which it appertains to make and use the same.

This invention relates to switch-throwing devices.

One object is to provide an exceedingly simple, inexpensive, durable, and efficient device of the nature stated.

Another object resides in the provision of a switch-throwing device embodying such characteristics that it may be readily operated and automatically thrown to its normal position when not in use.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a side elevation including the front portion of a car, the dotted lines showing the lowered position of the switch-throwing rod. Fig. 2 is a vertical sectional view of the switch-throwing device. Fig. 3 is a detail sectional view illustrating the connection of the short stub in the switch-throwing rod. Fig. 4 is a detail view of a switch.

Referring now more particularly to the accompanying drawings, the reference character 1 designates a portion of the front of a car, the platform thereof having an opening 2 therein in which is fitted a casing 3. This casing projects above and below the platform of the car and is prevented from falling through the opening in which it is mounted by reason of a flange 4, formed integrally with the cylinder or casing 3 for engagement with the upper face of the platform, as shown.

An operating-rod 6 is mounted for sliding movement within the casing 3 and is provided at its lower end with a blade 7, de-

signed to contact with the tongue 8 of the switch for the purpose of directing the car straight ahead or round a curve at a switch without necessitating the motorman or conductor leaving the car. This operating-rod 6 is held normally within the casing with its blade 7 contacting with the lower end of the casing through the instrumentality of a helical spring 9, which surrounds the operating-rod within the casing.

Formed in the upper end of the casing is a longitudinal slot 10, provided with a notch 11 at its lower end. A stub 12 is screw-threaded for engagement with the operating-rod 6 near its upper end for engagement in the slot 10 for guiding the operating-rod in its vertical movement, and the notch 11 is provided at the end of the slot for the purpose of permitting the stub 12 to be turned thereinto by operating the handle 13, so that the blade 7 of the operating-rod may be held in its lowered position for engagement with the tongue 8 of the switch. It will thus be seen that the stub 12 is detachable, so that in the event of breakage it may be readily replaced by a new one.

From the foregoing it will be understood that the purpose of the invention is to operate switches without necessitating the motorman or conductor leaving the car and that when the switch is approached it is simply necessary to grasp the handle 13 of the operating-rod 6 and force the latter downwardly until the stub 12 reaches the notch 11, when the handle is twisted slightly, throwing the switch and preventing upward movement of the operating-rod until the handle is turned in the reverse direction, when the aforesaid helical spring will automatically lift the operating-rod to its normal position.

What is claimed is—

1. The combination with a car including a front platform, having an opening therethrough, a casing mounted in said opening and projecting above and beneath the platform and provided with a collar for engagement with the upper face of the platform, an operating-rod mounted within the casing and provided with a plate for operating the switch, said casing having a longitudinal slot arranged in its upper end and communicating with a notch in the casing, the aforesaid operating-rod having a screw-threaded recess therein, a stub having screw-threaded engagement in said recess for operation in said slot and

notch, and a helical spring surrounding the operating-rod within said casing to hold the rod normally in its elevated position.

2. A switch-throwing device comprising a casing having a slot arranged longitudinally thereof and communicating with a notch of the casing, an operating-rod mounted for sliding movement within the casing and having a screw-threaded recess, a stub having screw-threaded engagement in said recess for coöperation with said slot and notch to guide the

rod in its sliding movement and to hold it in its downward position, and a helical spring surrounding the rod within the casing to lift the rod and hold it normally in its upper position. 15

In testimony whereof I affix my signature in presence of two witnesses.

THOMAS J. COLBURN.
